UNITED STATES PATENT OFFICE

167,779

PNEUMATIC TIRE

Audrey H. Steadman, Detroit, Mich., assignor to
United States Rubber Company, New York,
N. Y., a corporation of New Jersey

Application November 7, 1951, Serial No. 17,318

Term of patent 14 years

(Cl. D90—20)

To all whom it may concern:

Be it known that I, Audrey H. Steadman, a citizen of the United States of America, residing at Detroit, county of Wayne, and State of Michigan, have invented a new, original, and ornamental Design for a Pneumatic Tire, of which the following is a specification, reference being had to the accompanying drawing, forming part thereof, wherein:

Fig. 1 is a perspective view of a pneumatic tire, showing my new design, the dotted lines indicating the repetition of the pattern shown in full lines;

Fig. 2 is a fragmentary enlarged top plan view thereof;

Fig. 3 is a fragmentary side elevational view thereof;

Fig. 4 is a sectional view taken substantially along line IV—IV of Fig. 3; and

Fig. 5 is a sectional view taken substantially along line V—V of Fig. 2.

I claim:

The ornamental design for a pneumatic tire, substantially as shown and described.

AUDREY H. STEADMAN.
